UNITED STATES PATENT OFFICE.

EDWARD ERICKSON, OF LYNN, MASSACHUSETTS, ASSIGNOR TO VICTOR SHOE MACHINERY COMPANY, OF BOSTON, MASSACHUSETTS, A CORPORATION OF MASSACHUSETTS.

PRESSER-FOOT MECHANISM FOR SEWING-MACHINES.

1,133,229.

Specification of Letters Patent. Patented Mar. 23, 1915.

Application filed April 21, 1913. Serial No. 762,729.

To all whom it may concern:

Be it known that I, EDWARD ERICKSON, a subject of the King of Sweden, and a resident of Lynn, in the county of Essex and State of Massachusetts, have invented certain new and useful Improvements in Presser-Foot Mechanisms for Sewing-Machines, of which the following is a specification.

10 This invention relates to shoe sewing machines and particularly to the presser foot mechanism and means automatically controlled by the operation of the presser foot mechanism for measuring the required 15 length of thread for varying thicknesses of material.

It consists of certain novel features of construction and arrangement of parts which will be fully understood by reference to the description of the drawing and 20 to the claims hereinafter given.

The drawing consists of a transverse section of a sewing machine showing a presser foot mechanism and thread measuring 25 mechanism controlled thereby, said mechanisms embodying the features of the present invention.

In the drawing, 10 is a framework having mounted thereon the revoluble shaft 11, 30 to which is keyed a disk 12 having formed therein the cam paths 13 and 14. In the cam path 13 is a roller 15 mounted upon a stud in the end of a lever 16 movable about a pivot 17 mounted in the frame 10. This 35 pivot 17 is adapted to be oscillated in the frame 10 and is provided with peripheral teeth forming a pinion 18. The outer end of the lever 16 is provided with a guideway having parallel guide-walls 19-19^x extending transversely of said lever. Interposed between the guide-walls 19-19^x is 40 a slidable member 20 having formed there-in rack teeth 21 engaging with the peripheral teeth of the pinion 18. Secured to the 45 slidable member and extending laterally therefrom is the member 22, to which is secured the presser foot 23, the lower end of which has an operating face 24 parallel with the upper face 25 of the work support 50 26. In the drawings the presser foot is shown in the position assumed when no work is being acted upon. It is obvious that when the slidable member 20 is moved transversely of the outer end of the lever

16 the lower face 24 of the presser foot 23 55 and the upper face 25 of the work support 26 will remain constantly in parallelism when in gripping contact with the work in whatever position the presser foot may assume, it being understood that when said lever 16 is moved about its pivot by the throw of the cam 13 the face 24 is free from gripping pressure upon the work. This is of great advantage, as by means of this construction the operating face 24 of the 65 presser foot 23 when gripping the supported work always has an equal grip thereon, while in other forms of presser foot mechanisms when the position of the presser foot changes the operating face 24 is inclined 70 so that the gripping surface is continually being diminished. Secured to the fulcrum member 17 is an arm 27 adapted to be manually controlled to adjust the presser foot 23 relative to the lever 16, and 75 to accommodate it to varying thicknesses of material. This is accomplished by the operator moving the arm and turning the pinion 18, raising and lowering the presser foot 23 at will. The movement of the slidable member 20 in one direction is limited 80 by the member 22 coming in contact with the shoulder 28 on the lever 16 while the movement in the opposite direction is controlled by means of the spring 29 surrounding a guide rod 30 extending upwardly from the member 22 and through a hole in the member 31 secured to the lever 16, said hole being larger than the rod 30. The spring 29 is so light that it simply 85 retains the face 24 of the presser foot 23 in light contact with the work but does not create any effective pressure thereon, the only positive pressure upon the work being 90 that created by the cam path 13. 95

To permit work to be placed upon the work support 26, it is necessary, by means of the arm 27, to lift the presser foot 23 against the tension of the spring 29, thus separating the members 22 and 16. As 100 soon as the work is properly positioned the member 20 will be moved downwardly by the spring 29 and the presser foot 23 will be moved downwardly with its face 24 in light contact with the work, but at this time 105 there is comparatively no pressure thereon.

The main portion of the cam path 13 retains the operating face 24 of the presser

- foot 23 in gripping contact with the work upon the support 26, but when it is desired to move the work along the support the roller 15 of the lever 16 moves into the portion 32 of said cam path 13, thereby causing the gripping pressure of the presser foot to be removed from the work temporarily while said work is being moved upon the support into a new position.
- 10 When the cam throw 32 operates upon the lever 16 to move its front end upwardly the gripping pressure of the presser foot will be removed from the work, and while the roller 15 remains in the throw 32 the only pressure 15 upon the presser foot will be that of the light spring 29 surrounding the rod 30 which will retain the presser foot in light contact with the work. This light pressure will not prevent the feed of the work beneath the presser foot when the material is of substantially the same thickness or when it decreases in thickness as fed. When the material decreases in thickness the spring 29 will move the presser foot down to a new 20 position without effecting any change in the position of the lever 16. When as fed the material increases slightly in thickness, the presser foot will be forced further into the work. When any material increase in the 25 work occurs as it is fed the position of the presser foot must be changed by the operation of the arm 27. The slide 20 fits closely the guide walls 19, 19^x, and there is usually sufficient friction between the contacting 30 surfaces to permit the presser foot to be raised from the work when the roller 15 enters the throw 32 and the work will be fed before the spring 29 will overcome the friction and force the presser foot downwardly 35 into light contact with a new portion of the surface of the material. While the presser foot is bearing upon the work the awl pierces the material from the under side and tends to lift the material from the work 40 support, and when the awl has pierced the material but before it has finished its stroke, the presser foot will be lifted, the movement of the lever 16 permitting the material to be lifted from the support by the continued upward movement of the awl. At this time 45 the feed takes place and the increased space between the presser foot and work support at this time takes care of the varying thicknesses of material within certain limits.
- 50 55 When the awl is withdrawn the spring 29 acts to force the material into contact with the work support and the presser foot into contact with the work. This movement of the front end of the lever 16 upwardly relatively to the member 22 closes partly the space between the members 22—16 so that when the cam 13 next operates upon the lever 16 the face 24 of the presser foot 23 will be moved downwardly below its former position, thereby effecting a gripping pressure 65 upon the work. The various cycles of the cam 13 will then cause the presser foot to oscillate from a gripping position to a non-gripping position and vice versa. If the work is of the same thickness throughout 70 the relative positions of the lever 16 and member 22 will remain unchanged but if the thickness of the material varies, the relative positions of the member 22 and lever 16 will be changed automatically in the manner just 75 described. For instance, if the material becomes thinner as it is fed the presser foot 23 will be moved into light contact with the work by the action of the spring 29, thus decreasing the space between the member 22 80 and lever 16, but when the throw 32 again moves the lever 16 about its pivot to lower the presser foot 23 the gripping pressure thereon will be uniform with that upon the thicker part of the material. In other 85 words, the presser foot will be adjusted automatically to adapt it for various thicknesses of material, but when the gripping pressure is given by a fixed cam throw 32, the gripping pressure will always be uniform 90 without regard to the thickness of the material being acted upon.
- 95 When the lever 16 is moved about its pivot in either direction by the cam throw 32 the relative position of the member 22 thereto will not be changed by any power applied to said lever, the changes in the relative positions of the lever 16 and member 22 being effected always by power of the spring 29 which returns the face 24 of the 100 presser foot 23 into contact with the upper face of the material being fed beneath it, this being true whether the material is increasing or decreasing in thickness. It must be understood that at the time of feeding the 105 material, the pressure of the presser foot thereon is reduced to a minimum.
- 110 While the slide 20 may be moved relatively to the lever 16, it is obvious that when the cam 13 acts on the left end of the lever 16 this lever will be moved about its pivot 17 and carry the members 22—23 therewith, the presser foot 23 being caused thereby to give a gripping pressure upon the work on the support 26. This action is due largely 115 to the location of the pivot 17 adjacent to the sliding member 20 so that when said lever 16 is moved about its pivot while the presser foot 23 is in contact with the work the slide 20 will be cramped between the 120 guide walls 19—19^x on the lever 16 and by this cramping operation said slide will be prevented from moving transversely of the lever 16. Consequently when the left hand end of the lever is moved upwardly by the 125 cam 13, the operating face 24 of the presser foot 23 will be forced into the yielding material upon the work support 26 and firmly

grip the same until the roller 15 moves into the throw 32 and causes the gripping pressure of the presser foot to be released.

The lower end of the slidable member 20 is forked as indicated at 33 and the projecting ends 33^x are provided with passages through which extends a thread 34, this thread coming from any suitable source of supply and after leaving the slidable member 20 passing through any suitable wax pot, any well-known take-up device, and then through the work support 26 to the work. As these mechanisms form no part of the present invention, and any well-known constructions may be used, they are not illustrated in the drawing.

In the slot 33 is adapted to move the pin 35 mounted in the extreme end of a lever 36 pivoted at 37 to the frame 10 and provided at its opposite end with a truck or roller 38 extending into the cam path 14. This cam path is provided with a throw adapted to oscillate the lever 36 at the proper time to measure off the given quantity of thread for the stitch, the pin 35 in doing this moving longitudinally of the slot 33. The thread 34 in crossing the slot 33 passes beneath the stud or pin 35 and it is obvious that if the slidable member 20 was always in the same position a given length of thread would always be measured by the oscillation of the lever 36 and the movement of the pin 35 in the slot 33. It is desired, however, to measure off different lengths of thread for different thicknesses of material, and this is readily accomplished by means of the slidable member 20, it being self-evident that when the presser foot 23 is raised the thread-carrying passages in the lower end 40 of the slidable member are similarly raised into a new position corresponding with the thickness of the material and when in this raised position a greater quantity of thread will be drawn from the source of supply by the movement of the pin 35 in the slot 33, the lowermost position of said pin being the same under all conditions. When the take-up device is operating, the pin 35 will be in its highest position and the pin 40 on the lever 36 will coat with the fixed pin 41 to clamp the thread to prevent it being fed. It is obvious, therefore, that not only does the presser foot 23 accommodate itself automatically to varying thicknesses of material on the work support 26 but it automatically provides at the same time for varying lengths of threads corresponding to the thicknesses of material through which the thread is to be fed.

It is believed that the operation and many advantages of this invention will be fully understood from the foregoing description.

Having thus described my invention, I claim:

1. The combination of a pivoted cam-con-

trolled lever provided with parallel guide walls; a member supported by said lever and movable concentrically therewith about its pivot adapted to be reciprocated endwise between and lengthwise of said guide walls; 70 a work support; and a presser foot secured to said reciprocating member.

2. The combination of a pivoted cam-controlled lever; a member carried thereby and slidable transversely thereof; a work support; 75 and a presser foot secured to said slid- able member.

3. The combination of a pivoted cam-controlled lever; a member carried thereby and slidable transversely thereof; a work sup- 80 port; a presser foot secured to said slid- able member; and means for moving said slid- able member independently of said lever.

4. The combination of a pivoted cam controlled lever; a slidable member normally 85 positioned thereon and movable therewith; a work support; a presser foot secured to said slidable member; and manually con- trolled means for moving said slidable member transversely of said lever. 90

5. The combination of a pivoted cam-controlled lever; a slidable member normally positioned thereon and movable therewith, said member being provided with rack teeth; a work support; a presser foot secured 95 to said slidable member; a pinion at the pivotal axis of said lever engaging said rack teeth; and means for rotating said pinion.

6. The combination of a pivoted cam-controlled lever; a slidable member normally positioned thereon and movable therewith, said member being provided with rack teeth; a work support; a presser foot secured to said slidable member; a pinion at the pivotal axis of said lever engaging said 100 rack teeth; and a manually controlled arm 105 for rotating said pinion.

7. The combination of a pivoted cam-controlled lever having a guide-way extending transversely of its outer end; an oscillating fulcrum for said lever provided with peripheral teeth; a member slidable in said guide-way having rack teeth engaging the teeth on said fulcrum member; means for limiting the movement of said slidable member in one direction; a spring adapted to move said member in the opposite direction; a work support; and a presser foot on said 110 slidable member. 115

8. The combination of a pivoted cam-controlled lever having a transversely disposed guide wall at its outer end; an oscillating fulcrum provided with a pinion; a spring controlled slidable member interposed between said guide wall and pinion having rack teeth engaging the teeth of said pinion; a work support; and a presser foot on said 120 slidable member. 125

9. The combination of a pivoted cam-controlled lever; a slidable member carried 130

thereby and movable transversely thereof at a point intermediate the pivot and outer end; a presser foot on said slidable member; a work support; and means for moving said slidable member endwise.

10. The combination of a pivoted cam-controlled lever; a work support; a presser foot carried by and movable with said lever; means for adjusting the position of said presser foot relative to said lever; and means whereby the operating face of said presser foot may be retained in all positions parallel to the upper face of said support while work gripping pressure is being applied 15 thereby.

11. The combination of a pivoted cam-controlled lever; a work support; a presser foot carried by and yieldingly connected to said lever adapted to be moved substantially 20 vertically from said work support; means also carried by said lever adapted to retain said presser foot in contact with the work on said support; and means whereby work-gripping pressure may be imparted to said 25 presser foot.

12. The combination of a pivoted cam-controlled lever; a work support; and a presser foot yieldingly connected to the free end of said lever and having a transverse 30 reciprocating movement relative thereto adapted to be moved with it away from the work support; means for moving said presser foot in the opposite direction into contact with the work on said support; and 35 means whereby work-gripping pressure may be imparted to said presser foot by a con-

tinued movement of said lever to its normal position.

13. The combination of a pivoted cam-controlled lever; a forked member slidable 40 thereon adapted to guide a thread across the slot of said forked member; a work support; a presser foot secured to said slidable member; and a reciprocating thread engaging member operating in said slot to pull 45 a required length of thread from the supply.

14. The combination of a pivoted cam-controlled lever; a member carried thereby and slidable transversely thereof; a work support; a presser foot secured to said 50 slidable member; and a thread measuring device coacting with said slidable member and adapted to measure varying lengths of thread corresponding to the thickness of the material being operated upon.

15. The combination of a pivoted cam-controlled lever; a member carried thereby and slidable transversely thereof; a work support; a presser foot secured to said slid- 60 able member; a thread measuring device; and means whereby said slidable member may be moved independently of said lever and its position varied relative to said measuring device so that varying lengths of thread may be measured according to the 65 varying thicknesses of material.

Signed by me at 4 Post Office Sq., Boston, Mass., this 18th day of April, 1913.

EDWARD ERICKSON.
